[57] CLAIM

The ornamental design for a network interface for computer equipment or the like, as shown and described.

DESCRIPTION

FIG. 1 is a perspective view of a network interface for computer equipment or the like showing my new design, the electric cord being shown broken away for illustration purposes only;

FIG. 2 is a front elevational view thereof;

FIG. 3 is a right side elevational view thereof;

FIG. 4 is a top plan view thereof with the bottom plan view being a mirror image;

FIG. 5 is a left side elevational view thereof; and

FIG. 6 is a back elevational view thereof.

FIG. 2.

FIG. 1.

FIG. 3.

FIG. 4.

FIG. 6.

FIG. 5.
